UNITED STATES PATENT OFFICE.

WILLIAM A. BRAUER, OF NORTH TONAWANDA, NEW YORK, ASSIGNOR TO NIAGARA MUSICAL INSTRUMENT MANUFACTURING COMPANY, OF NORTH TONAWANDA, NEW YORK.

AUTOMATIC DRUM-BEATER FOR MECHANICALLY-OPERATED MUSICAL INSTRUMENTS.

965,435.

Specification of Letters Patent. Patented July 26, 1910.

Application filed September 8, 1908. Serial No. 452,065.

To all whom it may concern:

Be it known that I, WILLIAM A. BRAUER, a citizen of the United States, residing at North Tonawanda, county of Niagara, and 5 State of New York, have invented certain new and useful Improvements in Automatic Drum-Beaters for Mechanically-Operated Musical Instruments, of which the following is a specification.

10 This invention relates to automatic drum beaters for mechanically operated musical instruments.

As at present generally constructed, in devices of this character the drum sticks 15 are operated by a positive action which necessitates a continuous contact of the drum sticks with the head of the drum, thus deadening the vibration of the drum head, and such earlier devices have been noisy in the 20 operation of the drum stick actuating parts, if operated by gearing, or if a friction drive is employed, it has been liable to slippage and consequent omission of a stroke of a drum stick now and then.

25 The present invention seeks to obviate the defects heretofore existing in this class of devices by the provision of a novel mounting for the drum sticks, in connection with drum stick operating means, arranged in a 30 new manner, whereby the construction is simplified, the length of the stroke of the drum sticks may be regulated at will, and the hammers on the drum sticks are at all times kept out of contact with the drum 35 head, except when in actual operation, so that there is no deadening of the blow and the best effect is obtained from the drum head, beside which, a positive action is obtained.

40 The invention is set forth fully herein-after and its novel features are recited in the appended claims.

In the accompanying drawings:—Figure 1 is a perspective view; Fig. 2, a detail view 45 illustrating the hammer and drum stick connection; Fig. 3, a front elevation; and Fig. 4, a transverse section taken on the line 4—4 of Fig. 3.

Only so much of the mechanism of a 50 mechanically operated musical instrument is shown as will give a full understanding of the present invention.

The snare drum of the instrument is shown at 1 as having a drum head 2. The

numeral 3 designates a small bellows which 55 receives its air through a pipe 4 which is supplied by the main bellows of the instrument, the air supplied through the pipe 4 being controlled by suitable keys. This bellows 3 constitutes the prime means for controlling the operation of the drum sticks. 60

The operating mechanism is carried by a frame 5, to which is pivoted a rocker 6 by the shaft 7, said shaft having an arm 8, which is connected by a rod 9 to the bellows 3, so that upon admission of air to said bellows, the rod 9 will be elevated and the rocker 6 tilted against the action of a retracting spring 10, which tends to hold the rocker in retracted position. The drum 70 sticks 11 are pivoted on a pin 12 in independent slots 13, and at their upper ends carry hammers 14, which are carried by adjusting screws 15 threaded through the drum sticks. The numerals 16 designate 75 springs coöperating with the drum sticks and anchored to the rocker 6 whose tendency is to throw the drum sticks outwardly against a stop plate 17 on the rocker 6. It will thus be seen that the drum sticks are 80 collectively mounted for rocking toward and away from the drum head 2, but are independently actuatable and the hammers thereof are independently adjustable.

Mounted in the frame 5 is a shaft 18 carrying star cams 19 and 20 arranged with their teeth in relative staggered relation which are adapted to coöperate with the lower ends of the drum sticks when the bellows 3 is inflated and the rocker 6 tilted, 90 but at other times, the said cams do not touch said drum sticks. The shaft 18 is continuously rotated from a suitable part of the musical instrument by a belt passing around a pulley 21 secured to said shaft. 95

Normally the shaft 18 is in continuous rotation, but the drum sticks are only operated when appropriate keys of the instrument are manipulated to admit air to the bellows 3, and when this occurs, the rocker 6 is tilted, 100 as shown by dotted lines in Fig. 4, whereupon the ends of the drum sticks are positioned for engagement by the star cams and said drum sticks are then alternately vibrated as long as the air supply to the bellows continues, but immediately it is cut off, the spring 10 restores the rocker to normal 105 position and while the shaft 18 continues

its rotation, the cams do not vibrate the drum sticks. Inasmuch as the hammers do not remain in contact with the drum head, there is no deadening of the vibration of 5 said drum head and, consequently, the best effect of the drumming operation is obtained. The adjustability of the hammers permits any desired regulation of the blow.

The stroke can be regulated by the amount 10 of air admitted to the bellows 3, thus enabling the operator to obtain any desired effect.

Having thus described my invention, what I claim as new and desire to secure by Letters Patent, is:

1. In a drum playing device, the combination with a drum stick, of a hammer carried thereby which is adjustable in general transverse relation thereto, and means for 20 operating the drum stick.

2. In a drum playing device, the combination with a pivoted supporting frame, of an

arm connected to the pivot of said frame, a spring coöperating with the frame, a controllable pneumatic device coöperating with 25 the arm to shift the frame in opposition to the spring aforesaid, drum sticks pivoted to the supporting pivot at a point offset from the pivots thereof, springs independent of the springs aforesaid which coöperate with said 30 drum sticks and are secured to the movable frame, and an actuating shaft and strikers carried thereby located to coöperate with the drum sticks when the frame is shifted by the pneumatic device, the spring which retracts the frame being adapted to hold it in such position that the drum sticks are normally out of operative position.

In testimony whereof, I hereunto affix my signature in presence of two witnesses.

WILLIAM A. BRAUER.
